(57) **CLAIM**

The ornamental design for a plastic container, as shown and described.

DESCRIPTION

FIG. 1 is a top, front perspective view showing our new design;

FIG. 2 is a bottom, front perspective view thereof;

FIG. 3 a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken line showing of a pour spout, threads, and central bottom surface shown in the drawing views is included for the purpose of illustrating environmental structure that forms no part of the claimed design.

1 Claim, 7 Drawing Sheets
